Filed Mar. 8, 1971, Ser. No. 122,255

Term of patent 3½ years

Int. Cl. D6—03

U.S. Cl. D6—157

FIG. 1 is a generally perspective view of the combined cabinet and table unit showing my new design;

FIG. 2 is a top plan view thereof;

FIG. 3 is a bottom plan view thereof; and

FIG. 4 is an end view looking from the right hand side of FIG. 2, on a slightly reduced scale, with the opposite end being a mirror image thereof.

I claim:

The ornamental design for a combined cabinet and table unit, as shown and described.
